UNITED STATES PATENT OFFICE.

LEWIS EDWIN COALE, OF LANSING, ILLINOIS.

DESIGN FOR A ROPE-TIGHTENER.

SPECIFICATION forming part of Design No. 27,472, dated August 3, 1897.

Application filed June 28, 1897. Serial No. 642,758. Term of patent 14 years.

To all whom it may concern:

Be it known that I, LEWIS EDWIN COALE, a citizen of the United States, residing at Lansing, in the county of Cook and State of Illinois, have invented and produced a new and original Design for Rope-Tighteners, of which the following is a specification, reference being had to the accompanying drawings, in which—

Figure 1 is a plan view of a rope-tightener, showing my new design. Fig. 2 is a view in side elevation thereof. Fig. 3 is a cross-sectional view taken on line 3 3 of Fig. 1, looking in the direction indicated by the arrows; and Fig. 4 is a similar view taken on line 4 4 of Fig. 1, looking in the direction indicated by the arrows.

As shown in the drawings, my design comprises a piece A, of wood, metal, or other material of an elongated shape, having near its middle portion laterally-extending projections *a*, which are beveled toward their edges. Outwardly and on one side of said projec-

tions the piece A is reduced, as at *a'*, and is then formed with an enlarged or rounded end B, which is downturned, as shown in Fig. 2 of the drawings. Through the end B is a hole or opening *b*, and through the body of the piece A, near its middle, is another hole or opening *b'*, which holes or openings are united by means of a groove or depression *b*² in the upper surface of the tightener. The lower surface of the piece A is formed with a groove or depression C, which extends to near the end of the piece A, opposite that having the hole *b* therein. Near said end is formed another opening *c* of any suitable size.

Having described my invention, what I claim as new, and desire to secure by Letters Patent, is—

The design for a rope-tightener as herein shown and described.

LEWIS EDWIN COALE.
